Application December 14, 1939, Serial No. 309,112

18 Claims. (Cl. 101—43)

This invention relates to grading machines of the kind which grade leather soles and similar blanks in accordance with the thickness of the thinnest spot of the blank or of a predetermined area of the blank as determined by the detector or measuring device.

The invention is applicable to grading machines generally and the expression "grading" means or mechanism as herein used (unless limited expressly or by the context to some particular kind of grading mechanism) is used in the generic sense established in this art and includes marking devices, visual indicators, evening devices and sorting devices.

For the purpose of illustration, however, the invention will be shown in two embodiments, one applied to a grading machine used for marking of the character described in the Johnston Patent No. 1,963,850, dated June 19, 1934, and the other applied to a grading machine used for visual indicating of the character described in the Cogswell Patent No. 1,636,487, dated October 2, 1928. Since the general characteristics of such machines are well known it will only be necessary to describe herein such parts as will aid in an understanding of the present invention.

For use in shoe making it is sometimes desirable to classify unevened cut soles according to their suitability for different purposes and at the same time to grade them in a manner appropriate to such purposes. For example, in that method of making shoes in which the inner sole is formed by splitting off a skeletonized inner sole from the margin of one side of the outer sole, leaving an opening or void in the middle region of the inner sole, the cut sole before it is evened down to the thickness of its thinnest area and before the inner sole is split off, must have a predetermined minimum thickness or grade measurement throughout approximately its whole length because the skeletonized inner sole is to be split off from the whole length of the sole including the shank and heel parts as well as the forepart, and the whole sole throughout its length must therefore have suitable body or thickness for that purpose. To illustrate, a sole having a minimum grade measurement throughout its length greater than seven irons may be the lightest or thinnest sole suitable for the requirements or the preference of the shoe manufacturer in practicing the method referred to.

On the other hand, soles having a minimum grade measurement of seven irons or less are suitable for other purposes, and for such other purposes the grade measurement of the heel or

shank part, or both, may be disregarded as immaterial and the grade of the sole may be determined by the grade measurement of the forepart only. In such case, if the sole is measured and graded throughout its entire length it might happen that although the forepart of the sole measures a minimum or six or seven irons for example, the sole is graded as a thinner sole, for example a five iron sole, due to a thin area in the heel or shank. This is wasteful and costly since the grade of the heel and shank is immaterial for the purpose intended and the sole is entitled to receive the higher rating of its forepart, which is all that matters for the intended use of the sole.

It will be understood that a batch of unevened soles coming to a grading machine commonly contains miscellaneous and varying grades or thicknesses of soles, and soles which are uneven from end to end. In order to classify such soles with regard to their full length grades, to determine whether they belong in the group of thicker soles (more than seven irons throughout, in the assumed example) or in the group of thinner soles (seven irons or less at some place, in the assumed example), and also to grade the soles of the thinner class according to the grade of a selected area only, for example the forepart or ball of the sole, it would be possible with existing machines first to measure and grade all soles throughout their lengths and then to sort out those falling below the minimum predetermined thickness and remeasure and regrade those as to the forepart only, either by machine or by hand. To illustrate such procedure, a sole first measured and graded as to its full length might show five or six irons, which means that there is some spot or area only five or six irons thick. This sole then might be measured and graded again as to its forepart only, omitting the heel and shank, and it might turn out that the forepart has a minimum measurement of seven irons, showing that the thin spot, five or six irons, which disqualifies the sole for the thicker class, is in the heel or shank. Since the grade of the heel and shank of such a sole is to be disregarded, the second measurement and grading of the forepart only shows that the sole rates as a seven iron sole in the thinner class. Thus, although it is possible to obtain the desired information and to classify and grade soles of the thicker class and soles of the thinner class, each in a manner appropriate to its intended use, this can be done with present machinery only by grading all soles

of the thinner class twice, which entails such an increased cost of time and money as to render the procedure objectionable or commercially impracticable.

The principal object of the present invention is to provide a machine which will eliminate the necessity of such double grading and will furnish the desired classification and grade the soles of each class in a manner appropriate to that class, all in a single operation as the soles pass successively through the machine.

In the accompanying drawings, which illustrate preferred embodiments of the invention,

Figs. 1 to 8 inclusive show the invention applied to the type of grading machine described in said Johnston patent, and Figs. 9 to 14 inclusive show the invention applied to the type of grading machine described in said Cogswell patent.

Fig. 1 is a side elevation, partly in longitudinal section, of parts of a grading machine of said Johnston type containing the invention;

Fig. 12 is an elevation of certain parts of Fig. 10 as viewed in the direction of the arrow *a* applied to Fig. 10;

Fig. 13 is an elevation of the bracket attachment for supporting the supplemental "start-grading" pawl hereinafter described; and

Fig. 14 is a detail of a push bar hereinafter described.

The machine shown in Figs. 1 to 8 inclusive will be first described.

The soles *S* which are to be graded are stacked in a magazine or hopper *10*, Fig. 1, and are fed forward from the bottom of the stack one at a time by an intermittently operated feeding mechanism of known construction, including a link *11* and a crank arm *12*. The feeding mechanism advances the soles one at a time from the bottom of the stack, heel end foremost, and delivers each into the bite of a pair of feeding and measuring rolls *13* and *14* which are continuously driven as usual. As the forward end of each sole emerges from between the rolls *13* and *14* it engages a trip arm or lever *15*, Fig. 2, which forms a part of a cam *16* pivotally mounted at *17* on the frame of the machine. In its forward movement the sole swings the arm *15* and cam *16* thereby causing the cam *16* to raise a pivoted arm *18* and a weighted rod *19* pivotally suspended from the free end of arm *18*, for the purpose hereinafter explained.

As the sole emerges from between rolls *13* and *14* it also passes into position between a presser

bar *20* and a traveling endless conveyor chain *21*, which latter propels the blank through the machine in the usual way.

As the sole advances, its leading end engages 5 and raises a trip *22* depending from and adjustable on an arm *23* which is fast on a transversely disposed rock shaft *24*. Fixed to the outer end of this rock shaft *24* is an arm *25*, Figs. 1 and 2, to the free end of which is pivotally connected the upper end of a weighted rod *26*. The lower end of the rod *26* normally holds the usual "start-grading" pawl *27* out of engagement with its ratchet segment *28*, but when the rod *26* is thus lifted by the advancing sole the pawl *27* drops by gravity upon its ratchet *28*. No minimum measurements are preserved by the pawl *27* until a predetermined length of the sole has passed through rolls *13*, *14* and trip *22* is lifted, at which time a selected part of the sole, for example the forepart or ball, is entering the measuring rolls. The region whose minimum measurement is thus to be preserved may be varied by adjusting the trip *22* lengthwise of the arm *23*. The trip *22*, the pawl and ratchet *27*, *28* and the mechanism connecting the trip to the pawl constitute the usual controlling mechanism associated with the transmitting mechanism to preserve the minimum measurement which is to be transmitted to the grading means.

As the sole advances farther its leading end engages and depresses the trip arm *29*, which causes the automatic operation of the marking or stamping wheel *30* and also initiates a single rotation of crank arm *12* of the feeding mechanism, all in the usual way. Thus, the depression of the trip *29* results in the sole being stamped or marked according to the setting of the marking wheel and also causes the next succeeding sole to be fed forward from the magazine *10*. The first sole is carried forward and discharged from the machine by the conveyor chain *21*.

The lower measuring or detecting roll *14* is yieldingly supported and yields downwardly upon the entrance of a sole between the rolls *13* and *14* and responds to variations in thickness of the sole as it passes between the rolls. The vertical displacement of the measuring roll *14* acts through the usual transmitting mechanism to adjust the grading means, in the present instance the marking wheel *30*. Part of said transmitting mechanism rotatively adjusts the shaft *36* on which the ratchet wheel *37* is fixed, and the rotative adjustment of shaft *36* acts through another part of the usual transmitting mechanism to adjust the usual slide *38*, by which the marking wheel *30* is rotatively adjusted according to the thickness of the thinnest measurement as determined by the measuring roll *14* and preserved by the controlling mechanism.

When the advance end of the sole raises the trip *22* and rocks the shaft *24* an arm *39* fixed to shaft *24*, Figs. 2 and 3, is swung upwardly in a direction away from a roller *40* which is carried at the end of a lever *41*, thereby premitting a spring *42*, Fig. 1, to lower the usual gate *45* on to the top of the passing sole. When the rear end of the sole passes from beneath the gate *45*, the gate drops by gravity, assisted by the spring *42*, and acts to throw the usual "stop-grading" pawl *43* into engagement with the ratchet segment *44* on the ratchet wheel *37*.

The parts thus far described and their mode of operation (excepting trip lever *15* and the mechanisms controlled thereby) may be of usual and known construction and mode of operation, and

a more detailed description of them, and of certain other mechanisms associated therewith which are well known and are not herein shown, will not be necessary to an understanding of the present invention.

According to the present invention a second controlling mechanism is combined with the first and with the grading means in the manner now to be described.

The ratchet segment 28 of the usual controlling mechanism, Figs. 1, 3, 4 and 5, is fastened in usual position to the web of a wheel 37 by means of two screws 46 which occupy threaded apertures in said web. A supplemental ratchet segment 47 is also fastened to the wheel 37 in a position alongside the usual ratchet segment 28 by means of the same two screws 46. Associated with the supplemental ratchet segment 47 is a supplemental "start-grading" pawl 48, pivotally mounted on stud 49 which also carries the usual "start-grading" pawl 27. The supplemental pawl 48 is made with a tailpiece 50 which extends under the lower end of the weighted vertically movable rod 19.

The supplemental segment 47 is made with a pair of ears 51 formed with apertures 52 to receive the ends of screws 46, the holes 52 being somewhat larger than the screws so that the supplemental segment can be adjusted to a limited extent in any direction on the web of wheel 37. Nuts 53 on the screws 46 clamp the supplemental segment in its adjusted position.

A ratchet shield 56 is clamped to one side of the supplemental ratchet segment 47 by means of screws 55. The shield 56 has a salient arcuate portion 57, coincident with or just above the tops of the teeth of the supplemental ratchet segment 47, another portion of the peripheral surface of the shield 56 being recessed to leave the ratchet teeth unobstructed. The shield is also formed with arcuate slots 58 which provide for adjustment of the shield angularly on the ratchet segment so that the inner end 59 of the salient or shielding part may be positioned as desired with relation to the teeth of the supplemental ratchet.

The operation of the machine is as follows. Let it be assumed that it is to be determined which of the soles have a minimum grade measurement of more than seven irons everywhere throughout their length (e. g. a measurement of seven and one-half irons or more) and that such soles are to be marked (graded) in accordance with the thinnest part found; and that all other soles having minimum measurements of seven irons or less somewhere in their length are to be marked (graded) in accordance with the thinness part of a selected area only, for example the forepart or ball of the sole.

The ratchet shield 56 is then adjusted and set so that the salient or shielding surface 57 shields all of the ratchet teeth on ratchet segment 47 corresponding to thickness measurements of less than seven irons.

It will be understood that the adoption of seven irons as a dividing line between the two classes of soles is for the purpose of illustration only and that some other measurement than seven irons might be selected, in which case the shield 56 would be adjusted to shield the ratchet teeth corresponding to the range of the supplemental ratchet to be blanked out.

When a sole enters the machine its first action upon the emergence of its advance end from between the feeding and measuring rolls 13, 14, is 75

to swing trip lever 15 and cam 16 and thereby lower the supplemental pawl 48 upon the supplemental ratchet segment 47 or the shield surface 57, as the case may be. The swinging cam-arm 5 16, 15, is yieldingly held in its normal position by a spring 61, Fig. 3, and carries an adjustable stop screw 63 which rests against the frame of the machine.

If the sole throughout its length has a minimum thickness of more than seven irons the pawl 48 will engage the unobstructed part of the ratchet segment 47 and the measurement and grading will proceed in the usual way; and when the blank or sole reaches and lifts the trip 22 15 the regular "start-grading" pawl 27 will be lowered into its ratchet segment 28, but no change in operation will result therefrom since the two pawls will merely act in conjunction (unless a thinner measurement, less than seven irons, is 20 encountered, in which case the pawl 48 will ride up on the shield and the grading will be controlled by the pawl 27 alone).

If however the sole has an area somewhere in its length of seven irons thickness or less, that 25 fact will be determined and the sole will also be graded as to a predetermined part of its area, such as the forepart of the sole, in the manner now to be explained. If the thin spot of seven irons or less is in the advance end of the sole, which is the heel and shank part, the supplemental pawl 48 when lowered will rest on the shield surface 57 and therefore be inoperative to lock the supplemental "start-grading" ratchet 47, and as the heel and shank part of the sole 30 move forward between the measuring rolls 13 and 14 variations in thickness will merely cause the ratchet segment 47 to move back and forth idly while the supplemental pawl 48 slides on the shield surface 57, unless a thickness is encountered as great as seven irons, whereupon the pawl 48 will engage the first tooth of the ratchet segment 47 beyond the shielding surface 57 and lock the segment against movement in response to 35 thicker measurements. When the heel and shank part of the sole have passed the measuring rolls 13, 14, and the advance end of the sole lifts the trip 22, the regular "start-grading" pawl 27 is lowered into its ratchet segment 28 and thereafter, as the forepart of the sole (which is the trailing end) passes between the measuring rolls, each successive thinner measurement in the forepart will be determined and preserved by the pawl 27 notwithstanding the pawl 48 may be 40 riding on the shield.

Thus, if the heel or shank part has a place 45 measuring as low as seven irons or less that fact will be determined because the supplemental pawl 48 upon slipping off the shield will first engage the seven iron tooth of the ratchet and will not record any greater measurement, indicating that there was a spot or area at least as thin as seven irons. The actual minimum measurement of that region is not material so long as it is shown that there is an area at least as thin as seven irons, which disqualifies the piece for the thicker class above mentioned. When the ball or forepart of the sole enters between the measuring rolls and the regular "start-grading" pawl 70 27 goes into action, the grade measurement from that point on will proceed under the control of pawl 27, notwithstanding the pawl 48 may be riding idly on the shield.

It will be clear that after the trailing end of the sole has passed the swinging trip arm 15

and released the arm, permitting it to return to its normal position, thereby lifting the supplemental pawl 48 to inoperative position, the pawl 27 will continue to hold the ratchet wheel 37 in its adjusted position until the trailing end of the sole clears the trip 22. When the sole passes beyond the trip 22 the latter falls and acts through the usual mechanism to disengage both pawls 27 and 43 from the ratchet wheel 37.

The above described improvement may be permanently embodied in a grading machine or applied as an attachment to a grading machine of the character disclosed in said Johnston patent by merely adding a few parts thereto without material alteration of the existing machine. Moreover, if it is not desired to use the supplemental controlling devices in the grading of any particular lot of soles they may be rendered inoperative and the machine may be otherwise restored to its old mode of operation by merely disconnecting spring 61 and swinging the cam arm 16, 15, into a position outside of arm 18.

Referring now to Figs. 9 to 14 showing the invention applied to a machine for visually indicating grade measurements of the type described in said Gogswell patent, the soles S are stacked in a magazine 70 and are automatically fed from the bottom of the stack, heel and foremost, by the usual intermittently operated feeding mechanism including a link 71 and crank arm 72. During the first part of the movement of the feeding mechanism the gate trip 73 is lifted to permit the passage of the sole to the continuously driven measuring and feeding rolls 74, 75. As soon as the sole is under the gate trip 73 the latter falls and rests on top of the passing sole. The same action which raises the gate 73 withdraws the "stop-grading" pawl 76 from its ratchet wheel 77, Figs. 10 and 12, in the usual manner.

The visual indicator comprises a dial 78, showing a scale in terms of irons, and a pointer 79 traversing the scale and fixed to a rotatable shaft 80. Two ratchet wheels 77 and 83 are also secured to the shaft 80. At the outer end of shaft 80 is also fixed a pinion 81, Fig. 10, in mesh with the usual rack (not shown) on the upper end of a rod 82, Fig. 9. The lower end of rod 82 is provided with a rack in mesh with a gear segment on the end of arm 84. Arm 84 is fast on rock shaft 85. Also fast on rock shaft 85 are arms 86 which are connected to the lower measuring roll 75 through rods 87. When a sole enters between the two measuring rolls 74, 75 the latter roll is depressed against the pressure of a spring 88, Fig. 9, and acts through rods 87, arms 86, arm 84, rod 82 and pinion 81 to rotate the two ratchet wheels 77 and 83 and the pointer 79 in a clockwise direction.

The usual controlling mechanism for machines of this type to preserve the minimum measurement includes the "start-grading" pawl 89 which is normally held out of engagement with its ratchet 83 by an arm 90 which is actuated by the horizontal arm 91. Depending from arm 91 and adjustable lengthwise thereof is a trip 92 in the form of a roller in the path of the blank.

The parts thus far described may be of known construction and for a more detailed description thereof reference may be had to said Cogswell patent.

Combined with the foregoing is a second or supplemental controlling device now to be described. Journaled in a bearing provided at one side of the machine, as shown in Figs. 9 and 10, is a countershaft 93, the inner end of which ex-

tends over the bed plate 94 of the machine and is provided with a depending trip arm 95 which is close to the measuring rolls 74, 75, and in the path of the soles as they emerge from between the measuring rolls. The lower end of the trip 95 normally occupies a position within a longitudinal slot 96, Fig. 10, in the bed plate 94. The shaft 93 carries a cam 97 which acts against a shoulder 98 provided on a push bar 99.

One end of the bar 99 is provided with a slot 100 through which the shaft 93 extends and the other end of the bar is pivotally connected at 101 with a supplemental "start-grading" pawl 102, whose upper free end is associated with a sector of ratchet wheel 83. A spring 103 yieldingly urges the bar 99 toward shaft 93 and tends to move the supplemental pawl 102 toward the ratchet 83.

The supplemental pawl 102 is pivotally mounted at 104 upon a bracket 105. One end of the bracket 105 is made with an aperture through which the shaft 93 extends to support the bracket at that end and the opposite end of said bracket is made with a depending yoke 106, which embraces the upper margin of a member 107 constituting part of the frame of the machine. A vertical screw 108 threaded through the top of the yoke serves to regulate the height of the yoke end of bracket 105 and a horizontal screw 109 threaded through the side of the yoke serves to clamp the yoke fixedly to the frame. By adjusting the screw 108 it is possible to position the upper end of the supplemental pawl 102 in proper relation to the ratchet wheel 83. A spring 110 connected with an arm 111 fixed to the outer end of shaft 93 normally holds said arm against a stop 112 on the frame of the machine with the trip 95 yieldingly occupying its lowermost position in close proximity to the bite of the measuring rolls 74, 75.

Upon the outer side face of ratchet wheel 83 is provided a ratchet shield 113 having an apertured hub which is loosely fitted upon the end of shaft 80 but is securely clamped to the outer face 45 of the ratchet 83 by means of the usual nut 114 by which the ratchet wheels and pointer are clamped to the shaft 80. The periphery of the shield 113 is coincident with or slightly higher than the teeth of ratchet 83 so that when supplemental pawl 102 rests against the shield it is held out of engagement with the teeth of the ratchet. The shield 113 is formed with an arcuate slot 115 through which passes a set screw 116 to provide additional means for holding the shield against displacement and also to permit angular adjustment of the shield relative to the ratchet. In this way the upper end of the shield 113 may be positioned relatively to a selected one of the teeth of the ratchet 83.

The operation of the machine shown in Figs. 9 to 14, which is similar in principle to that of the other machine, is as follows. Assuming the same conditions as were assumed in connection with explaining the other machine, the ratchet shield 113 is adjusted and set so that it shields and prevents engagement of the supplemental "start-grading" pawl 102 with all of the ratchet teeth corresponding to thickness measurements of less than seven irons.

When a sole is first started forward into the machine the gate trip 73 is raised to admit the sole and at the same time the "stop-grading" pawl 76 is disengaged from its ratchet 77. The pointer 79 is now free to move in either direction since at this time the controlling pawls 89 and

102 are disengaged. Immediately after the entry of the sole under the trip gate 73 the latter falls and rests on top of the sole thereby still holding the pawl 76 disengaged so long as a sole is under the trip gate 73. The sole then enters between the measuring rolls 74 and 75 and immediately upon the emergence of its advance end from between the measuring rolls it engages and swings the trip 95 of the supplemental controlling mechanism toward the right as indicated by the arrow on Fig. 9. This movement acts through cam 97 and bar 99 to cause the supplemental "start-grading" pawl 102 to engage its segment of the ratchet 83 or the shield 113, as the case may be.

If the measurements of the sole are less than seven irons the pawl 102 will ride on the shield 113. If the measurements are seven irons or more the pawl 102 will engage the ratchet 83. When the sole reaches and lifts the trip 92 the regular "start-grading" pawl 89 will be caused to engage its segment of ratchet 83 and grade that part of the trailing end of the blank, for example the forepart of the sole, which thereafter passes through the measuring rolls.

When the trailing end of the blank passes out from under gate trip 73 the latter falls to the bed plate thereby causing the "stop-grading" pawl 76 to engage its ratchet 77 and so locking the indicator in its final adjusted position. When the sole passes clear of the feeding and measuring rolls 74, 75, it comes to rest and so remains until manually removed by the operator. After reading the indicator the operator pulls the sole out from the machine thus releasing the trips 95 and 92 to return to their normal positions and to disengage pawl 89 and supplemental pawl 102 from their respective segments of ratchet wheel 83. The drop of trip 92 also acts through the usual automatic mechanism to operate the feeding mechanism and advance another sole from the magazine 70 into the machine and the above described cycle of operations is repeated.

Thus it will be seen that in each embodiment of the invention there is associated with the grading means not only the usual controlling mechanism operated by the blank, including a pawl and ratchet for preserving the minimum measurement of a predetermined length of the trailing part of the blank, but also a second or supplemental controlling mechanism including a supplemental pawl and ratchet operated by the blank in advance of the regular controlling mechanism and therefore during the passage of a different part of the blank through the measuring rolls; and that the ratchet shield associated with the supplemental ratchet renders the supplemental controlling means inoperative to preserve the measurement of any area of the blank which is less than the predetermined thickness. Hence a selected length of the advance or leading part of the blank may or may not be graded depending on whether the minimum thickness is greater or less than a predetermined measurement and if less than such thickness that fact will be indicated, while a selected length of the trailing part of the blank will be graded notwithstanding the supplemental controlling pawl may be riding on the shield.

I claim:

1. A grading machine comprising measuring means, adjustable grading means, transmitting mechanism by which determinations of the measuring means are transmitted to the grading means, and two controlling mechanisms associated with the grading means each controlling

mechanism including a blank engaging means adapted to be tripped by the blank being graded during the passage through the measuring means of different areas of the blank to render the grading means effective and one of said mechanisms including means for rendering it inoperative during its measurement of that portion of the area so measured which is of less than a predetermined thickness.

10 2. A grading machine comprising measuring means, adjustable grading means, transmitting mechanism by which determinations of the measuring means are transmitted to the grading means, two controlling mechanisms associated

15 with the grading means each controlling mechanism including a blank engaging means adapted to be tripped by the blank being graded during the passage through the measuring means of different areas of the blank to render the grading means effective, and means to render one of said controlling mechanisms inoperative during the measurement of an area of the blank which is of less than a predetermined thickness.

3. A grading machine comprising measuring means, adjustable grading means, transmitting mechanism by which determinations of the measuring means are transmitted to the grading means, and two controlling mechanisms associated with the grading means each controlling

30 mechanism including a blank engaging means adapted to be tripped by the blank being graded during the passage through the measuring means of different areas of the blank to render the grading means effective, one controlling

35 mechanism being adapted to be rendered effective only during the measurement of a selected area of the blank, and the other controlling mechanism being adapted to be rendered effective during the measurement of a different selected area which is of greater than a predetermined thickness, and said last-named mechanism including means which renders it inoperative

40 during the measurement of the measurement of that portion of such area which is of less than a predetermined thickness.

45 4. A grading machine comprising measuring means, adjustable grading means, transmitting mechanism by which determinations of the measuring means are transmitted to the grading means, and two controlling mechanisms associated with the grading means each controlling mechanism including a blank engaging means adapted to be successively tripped by the blank being graded at different times during the passage of the blank through the measuring means, and means to render one of said control mechanisms inoperative during the measurement of an area of less than a predetermined thickness.

50 5. A grading machine comprising measuring means, adjustable grading means, transmitting mechanism by which determinations of the measuring means are transmitted to the grading means, two controlling mechanisms associated with the grading means each controlling mechanism including a blank engaging means adapted to be successively encountered by the blank being graded at different times during the passage of the blank through the measuring means, and means to render the first of said controlling mechanisms encountered by the blank inoperative during the measurement of an area of the blank which is of less than a predetermined thickness.

55 6. A grading machine comprising measuring means, adjustable grading means, transmitting

mechanism by which determinations of the measuring means are transmitted to the grading means, and two controlling mechanisms associated with the grading means each controlling mechanism including a blank engaging means adapted to be successively tripped by the blank being graded at different times during the passage of the blank through the measuring means, one of said controlling mechanisms being operated during the measurement of approximately the full length of the blank and the other of said controlling mechanisms being operated during the measurement of a predetermined length of the trailing end of the blank, the first named controlling mechanism including means to render it inoperative during the measurement of an area of less than a predetermined thickness.

7. A grading machine comprising measuring means, adjustable grading means, transmitting mechanism by which determinations of the measuring means are transmitted to the grading means, and two controlling mechanisms associated with the grading means adapted to be successively operated by the blank being graded at different times during the passage of the blank through the measuring means, each controlling mechanism including a ratchet and pawl and a trip in the path of the blank for actuating the pawl, one trip being positioned in advance of the other, means to prevent the pawl of the controlling mechanism first encountered from engaging its ratchet during the measurement of an area in the advance end of the blank which is of less than a predetermined thickness but to permit its engagement during the measurement of an area which is of greater than a predetermined thickness, and means to cause the engagement of the pawl of the other controlling mechanism with its ratchet only after a predetermined length of said advance end has passed through the measuring means.

8. A grading machine comprising measuring means, adjustable grading means, transmitting mechanism by which determinations of the measuring means are transmitted to the grading means, two controlling mechanisms associated with the grading means each controlling mechanism including a blank engaging means adapted to be successively engaged by the blank during its passage through the measuring means, one of said controlling mechanisms being operated during the measurement of approximately the full length of the blank and the other of said controlling mechanisms being operated during the measurement of a predetermined length of the trailing end of the blank, and means to render the first controlling mechanism inoperative during the measurement of an area of the blank which is of less than a predetermined thickness.

9. A grading machine comprising measuring means, adjustable grading means, transmitting mechanism by which determinations of the measuring means are transmitted to the grading means, and two controlling mechanisms associated with the grading means each controlling mechanism including a blank engaging means adapted to be engaged by the blank being graded during the passage through the measuring means of different areas of the blank to render the grading means effective, each controlling mechanism including a ratchet and pawl, and a ratchet shield for one ratchet to prevent the engagement of its pawl with a selected part of such ratchet.

10. A grading machine comprising measuring

means, adjustable grading means, transmitting mechanism by which determinations of the measuring means are transmitted to the grading means, and two controlling mechanisms associated with the grading means each controlling mechanism including a blank engaging means adapted to be engaged by the blank being graded during the passage through the measuring means of different areas of the blanks to render the grading means effective, each controlling mechanism including a ratchet and pawl, and a ratchet shield adjustably secured to one ratchet to prevent the engagement of its pawl with a selected part of such ratchet.

11. A grading machine comprising measuring means, adjustable grading means, transmitting mechanism by which determinations of the measuring means are transmitted to the grading means, and two controlling mechanisms associated with the grading means each controlling mechanism including a blank engaging means adapted to be successively engaged by the blank being graded at different times during the passage of the blank through the measuring means, each controlling mechanism including a ratchet and pawl, and a ratchet shield for one ratchet to prevent the engagement of its pawl with a selected part of such ratchet.

12. A grading machine comprising measuring means, adjustable grading means, transmitting mechanism by which determinations of the measuring means are transmitted to the grading means, and two controlling mechanisms associated with the grading means each controlling mechanism including a blank engaging means adapted to be successively engaged by the blank being graded at different times during the passage of the blank through the measuring means, each controlling mechanism including a ratchet and pawl, and a ratchet shield for the ratchet of the first of said controlling devices encountered by the blank to prevent the engagement of its pawl with a selected part of such ratchet corresponding with the measurement of an area of the blank which is of less than a predetermined thickness.

13. A grading machine comprising measuring means, adjustable grading means, transmitting mechanism by which determinations of the measuring means are transmitted to the grading means, and two controlling mechanisms associated with the grading means adapted to be successively operated by the blank being graded at different times during the passage of the blank through the measuring means, each controlling mechanism including a ratchet and pawl and a trip in the path of the blank for actuating the pawl, one of said trips being positioned to be operated by the blank after a predetermined length of the blank has passed through the measuring means and the other of said trips being positioned to be operated by the blank in advance of the first, and a ratchet shield to prevent the operation of the latter trip by the blank from rendering its pawl and ratchet effective during the measurement of an area of the blank which is of less than a predetermined thickness.

14. A grading machine comprising measuring means, adjustable grading means, transmitting mechanism by which determinations of the measuring means are transmitted to the grading means, and two controlling mechanisms associated with the grading means each controlling mechanism including a blank engaging means adapted to be engaged during the passage

through the measuring means of different areas of the blank being graded, each controlling mechanism including a ratchet and pawl, one ratchet being detachably fastened to the other, and a ratchet shield adjustably and removably secured to one ratchet to prevent the engagement of its pawl with a selected part of such ratchet.

15. A grading machine comprising measuring means, adjustable grading means, transmitting mechanism by which determinations of the measuring means are transmitted to the grading means, and two controlling mechanisms combined with the transmitting mechanism to govern the transmission to the grading means of certain of the determinations of the measuring means, said two controlling mechanisms each including means adapted to be operated by the blank being graded during the passage through the measuring means of different areas of the blank to render the grading means effective and one of said controlling mechanisms including means to render it inoperative during the measurement of an area less than a predetermined thickness.

16. A grading machine comprising measuring means, adjustable grading means, transmitting mechanism by which determinations of the measuring means are transmitted to the grading means, and two controlling mechanisms combined with the transmitting mechanism to govern the transmission to the grading means of certain of the determinations of the measuring means, said two controlling mechanisms each including means adapted to be operated by the blank being graded during the passage through the measuring means of different areas of the blank to render the grading means effective, and means to render one of said controlling mechanisms inoperative during the measurement of an

area of the blank which is of less than a predetermined thickness.

17. A grading machine comprising measuring means, an adjustable marker, transmitting mechanism by which determinations of the measuring means are transmitted to the marker, and two controlling mechanisms, each including a ratchet, a pawl and a trip in the path of the blank said tripping being engaged by the blank to actuate the pawl, and a ratchet shield for one ratchet to prevent one pawl from engaging its ratchet during the measurement of an area of the blank which is of less than a predetermined thickness but to permit its engagement during the measurement of an area which is of greater than a predetermined thickness, and means to cause the engagement of the other pawl with its ratchet during the measurement of a selected part only of the blank.

18. A grading machine comprising measuring means, a visual indicator, transmitting mechanism by which determinations of the measuring means are transmitted to the indicator, and two controlling mechanisms each including a ratchet, a pawl and a trip in the path of the blank said tripping being engaged by the blank to actuate the pawl, each ratchet consisting of a different segment of a common ratchet wheel, and a ratchet shield for one of said ratchet segments to prevent one pawl from engaging its ratchet segment during the measurement of an area of the blank which is of less than a predetermined thickness but to permit its engagement during the measurement of an area which is of greater than a predetermined thickness, and means to cause the engagement of the other pawl with its ratchet segment during the measurement of a selected part only of the blank.

JAMES W. JOHNSTON.
